AIRMAIL ENVELOPE

Julio A. Pichardo, New York, N. Y.

Application May 12, 1949, Serial No. 2,599

Term of patent 3½ years

(Cl. D59—8)

To all whom it may concern:

Be it known that I, Julio A. Pichardo, a citizen of the United States, residing at New York, in the county of New York and State of New York, have invented a new, original, and ornamental Design for an Airmail Envelope, of which the following is a specification, reference being had to the accompanying drawing, forming a part thereof.

In the drawing:

Fig. 1 is a front elevational view of an airmail envelope, showing my new design; and

Fig. 2 is a rear elevational view of the same.

I claim:

The ornamental design for an airmail envelope, as shown.

JULIO A. PICHARDO.
